UNITED STATES PATENT OFFICE.

ROBERT P. LAMONT AND EDMOND D. BRONNER, OF DETROIT, MICHIGAN.

ROOF.

SPECIFICATION forming part of Letters Patent No. 448,244, dated March 17, 1891.

Application filed September 20, 1890. Serial No. 365,592. (No model.)

To all whom it may concern:

Be it known that we, ROBERT P. LAMONT and EDMOND D. BRONNER, citizens of the United States, residing at Detroit, county of Wayne, State of Michigan, have invented a certain new and useful Improvement in Roofs; and we declare the following to be a full, clear, and exact description of the invention, such as will enable others skilled in the art to 5
10 which it pertains to make and use the same, reference being had to the accompanying drawings, which form a part of this specification.

Our invention relates more particularly to 15 the supporting and joining together of the roof-plates of a car or other structure, whereby there are no orifices or joints exposed on the uppersurface of the roof; and it consists in a combination of devices and appliances 20 hereinafter described and claimed.

In the drawings, Figure 1 is a plan view of 25 a portion of the roof of a car, and Fig. 2 is an edge view of the same. Fig. 3 is a perspective view of one of the roof-plates.

25 In carrying out the invention, A represents one of the members or beams of the roof to which the roof-plates are directly engaged and by which they are sustained. These members or beams are a peculiar shape, being substantially a T shape in cross-section, with the flanges a a curved or rounded downward. The plates B are made of sheet metal and corrugated, as at b, to strengthen them. The edge of each plate which is attached to 30 the cross-beam A is shaped as shown in Fig. 2, with a corrugation or ridge b' and the depending web or flange b². This depending web or flange is provided with bolt-orifices b³.

35 C is a packing, of tar-rope, rubber, or the like, placed between the corrugation b' and the flanges a a of the cross-beam, thus making a perfectly-tight joint.

D is a bolt passed through the depending flanges b² of the two top plates B and through 40 the web a' of the cross-beams, thus binding all three parts together and making a joint without a bolt or bolt-orifice being exposed on the surface of the roof. By this construction the ordinary batten now employed to 45
50 cover the joints between the plates is dispensed with, and the peculiar form of the

cross-beam not only renders the batten unnecessary, but it cheapens and strengthens the construction, and also, as above set forth, makes a joint without a break in the upper 55 surface.

We do not confine ourselves to curving the flanges a as shown, for obviously they can be otherwise shaped to house the ridged and flanged edges of the roof-plates. 60

What we claim is—

1. In a metallic-roof structure, the combination, with the roof-plates, each having a ridge or corrugation b' and dependent flange b², of the cross-beam formed with the upright 65 web a' and flanges a a, the flanges b² of two adjacent plates being engaged to the web a', substantially as described.

2. In a metallic-roof structure, the combination, with two adjoining roof-plates provided at their edges with ridges or corrugations b' and depending flanges b², of the cross-beam for supporting and engaging said plates, said beam having a web a', to which the depending flanges of the plates are engaged by 70 a through-bolt, and having also the flanges a a, which project over and cover the corrugations b', substantially as described.

3. In a roof structure, the combination of the cross-beam formed with the upright web 75 a' and flanges a a, the roof-plates B, provided adjacent to the edge with the corrugation b' and depending flange b², a suitable packing C, placed between the corrugations b' and flanges a, and a bolt passed 80 through the flanges b² and web a' for securing the parts together, substantially as described.

4. In a roof structure, the combination of a supporting member comprising a vertical 85 web a' and overhanging flanges a with metallic roofing-plates extending under the flanges and provided at their edges with flanges which are attached to the web, substantially as described. 90

In testimony whereof we sign this specification in the presence of two witnesses.

ROBERT P. LAMONT.
EDMOND D. BRONNER.
